AIRPLANE CONTROL

Wallace O. James, New York, N. Y.

Application January 24, 1934, Serial No. 708,152

5 Claims. (Cl. 244—83)

The invention relates to steering devices particularly suited to use in air planes for lateral and vertical steering, and for controlling the trim of the ship as in banking and overcoming side slip, etc.

An important purpose of the invention is to enable the direction of the flight of an airplane by simple manipulations corresponding closely to those required in steering an automobile, so that the actions which will be instinctive to many for effecting certain movements of a craft by reason of corresponding actions in directing land craft will be effective in controlling the airplane.

It is an important aim to present a construction which will increase the facility of human control and at the same time effect automatic control in trimming the ship both abeam and fore-and-aft.

It is a most important purpose to present a control useful in operating the rudder and ailerons effectively and easily for proper turns and for readily "levelling out" without requiring the operation of radically different members. I am aware of the use of two concentric hand wheels for operating respectively longitudinal and transverse balancing devices, and it is a purpose of my invention to improve on the use of such devices to the end that a peculiar effect in making turns may be obtained not hitherto possible with prior devices, and also to enable a peculiarly satisfactory coordination of the elevator control with the rudder and aileron controls. It is a further special aim to enable the operation of the ailerons and rudder simultaneously with a single wheel, which, however, is adapted to separate operation of the ailerons and rudder as required. It is a particular purpose to provide a device specially useful in making banked turns which may also serve with high effectiveness in other maneuvers, such as the "Immelman turn"; the "barrel turn"; for coming out of spins, and for other movements.

It is a specific object of the invention to effect an improvement in the construction of the hand wheel member used for ordinary operation where only simple banked turns, ascension and descent are involved. A further specific object is to provide a novel resilient device for holding the ailerons and rudder in neutral positions. A further aim is the perfection of a novel pedal control for elevators.

An important object of the invention is the perfection of an automatic balancing means particularly coordinated with the ailerons and rudder controls, as well as with the elevator control,

and constructed so that inherently the controls will operate to counteract variations from normal safe flying positions of the craft except when purposely operated contrariwise. This is also purposed to maintain automatically the normal 5 flight altitude initiated by the pilot.

Additional objects, advantages and features of invention reside in the construction, arrangement and combination of parts involved in the embodiment of the invention, as will appear from 10 the following description and accompanying drawings, wherein

Figure 1 is a schematic view of a control system in a plane embodying my invention.

Figure 2 is a detail of the pedal control therein. 15

Figure 3 is a detail of the neutralizing spring.

Figure 4 is a longitudinal sectional view of a control wheel and post unit embodied in my invention.

Figure 5 is a detail of the rack and weighted 20 gear in the rudder control.

Figure 6 is a schematic view showing the manner of automatic functioning of the rudder and aileron control in recovery from a "slip" or "skid" toward the left of the view. 25

Figure 7 is a similar view showing the functioning of the controls to overcome slip or skid to starboard, arrow *a* indicating the direction of a turn produced by manual operation of the rudder; arrow *b* showing the direction of the skid, 30 and arrow *c* coinciding with the depression of the port wing.

Figure 8 is a similar view showing the functioning of the controls in a skid due to manual operation of the rudder without banking. 35

There are illustrated the elements of an airplane of conventional form of today, including the usual rudder 10, ailerons 11 and elevator 12 constructed and mounted to operate in the familiar ways. The details of structure of the craft 40 otherwise being well understood, and comprising no novel part of this invention are not illustrated, and the manner of mounting the illustrated elements in such craft is well known.

In Figure 1 the elevator is operated by means 45 of a rod 13 extended longitudinally of the craft, connected at its rear end to the arm 14 fixed on and extending downward from the elevator. At its forward end the rod is connected to a depending arm 15 of a bell crank lever 16 pivoted beneath the foot board, the upper rearwardly extended arm 17 of the lever being connected to a flexible tape or cord 18 (see Fig. 3) normally wound on a drum 19, carried in a case 20, which has an opening 21 for the tape presented toward 50 55

the lever 16 on a radius of the lever midway of its extremes of movement. A volute torsion spring 22 is anchored to a fixed post 23 within the drum and connected at its outer end to the drum so as 5 to turn the drum and hold the tape yieldingly wound thereon. The arm 17 is thus held normally directly before the opening 21 and the parts are so proportioned that this is the neutral position 10 of the elevator control. The case 20 is shown mounted on a bracket 22' attached to the under side of the foot board 24.

On a foot board 24 the pedal post 25 is fixed, having a pedal 26 fulcrumed thereon as a lever of the first order. To the forward or toe end of 15 the pedal a rod 27 is pivoted, the latter being connected at its lower end to the end of the arm 17. The rear or heel end of the pedal is free and the lever is spaced from the board 24 sufficiently to permit its ends to be depressed alternatively. Depression of the forward end will cause the rod 13 20 and arm 14 of the elevator to be drawn forwardly and causing the lifting of the tail of the craft so that its nose is lowered and it is caused to go into a glide, or to tend to level out, if ascending. To 25 bring the nose of the plane up pressure is exerted by the pilot on the heel of the pedal. The pedal would preferably be located at the left of the pilot so that the right foot would be free for use with the usual foot throttle of the motor, or for applying brakes.

At a suitable part of the rod 13 a rack 28 is incorporated having a gear 29 meshed therewith and revolvably mounted on a fixed axis. This gear has connected thereto a pendulum or weight 30 35 perpendicular when the craft is on a normal course. If the pedal is free, and the ship is headed down, the weight swings forward, moving the rod 13 backward and causing operation of the elevator 12 to lower the tail of the craft and so 40 bringing it to and maintaining it on an even keel, or a position which will cause the ship to follow a course approximately a constant altitude. The reverse action occurs when the plane is headed upward.

45 A tubular steering post 31 is illustrated which may be mounted on a horizontal, or inclined axis, as found most convenient in order to incorporate the control and to suit the convenience of the pilot after the manner of an automobile steering column. This may be secured upon the foot board 24 or otherwise in any approved manner. In suitable fittings at its upper and lower ends ball bearings 32 are mounted supporting a hollow aileron control shaft 33. To the upper end of 50 this shaft an inner or lower rim section 34 of a split control wheel 35 is secured by a single fore and aft cross bar 36, having a hub formed with a concentric annular seat 37 in its outer side in which a bearing 38 is set, carrying the outer end of an inner hollow rudder shaft 39, to which a 55 transverse cross bar 40 is fixed carrying the outer or upper rim section 41 of the control wheel 35. Over the hub 42 of the spider 40 any usual switch, light, spark, or other levers 43 may be mounted in a familiar way, and from these any usual shafts or other connections (not shown) may be extended. The rim sections 34 and 41 are of a 60 shape in cross section that will together form a suitable contour to enable effective grasping of the two together in one hand, the palm on the outer one 41 and the fingers extending around the inner one 34. The cross-sectional form may be varied to improve the effects and functions desired and to enable proper grasping of the two rim sections.

As shown the proximal faces of the two sections are flattened and at an obtuse angle to the axis of the post, being inclined from adjacent the outer and upper spider 40 to a line inwardly of the inner or lower spider, so that in fact the opposed faces are conical. The exposed faces of the rim sections as here shown are rounded so that the two sections together have the form of an egg in cross section with its larger portion presented away from the post. The space between the sections is about one eighth of an inch. The inner spider may be flexible toward the outer one so that the two rim sections may be drawn together when grasped firmly, but should be rigid against flexure by rotation on the axis of the wheel. The purpose is that when in mutual contact, by friction or otherwise, there will be less likelihood of slippage of one section relatively to the other, until purposely released.

For moving the rudder there is a cable circuit 20 44 including two side members connected to respective ends of the cross arm 45 of the rudder and a transverse reciprocable rack 46 to which the side members are connected and by reciprocation of which they are operated to move the 25 rudder. This rack is extended equally in opposite directions from adjacent the shaft 39, and a gear 47 is fixed on the end of this shaft meshed with the rack, so that by rotation of the outer or upper rim section 41 the rack is moved to swing the 30 rudder. There is a second similar rack 48 parallel to the first and adjacent the end of the shaft 33, and this shaft carries a gear 49 meshed with the rack 48. From the ends of the rack 48 respective cables 50 are extended to the upwardly projected operating arms of the respective ailerons 35 41 and return connections may be made if desired in accordance with familiar practice. The gear 49 is formed with a normally lower weighted portion 51 which may be on either or both sides 40 of the gear and may be extended as desired, while the gear 47 is similarly weighted at its upper part as at 52 or with more radial extension, if desired.

The racks are both mounted on anti-friction devices 53 mounted on a suitable plate 54 45 carried by a bracket 55, which may be a continuation of the one 24' before referred to if the steering post is mounted on the foot board 24. Mounted on the plate 54 midway of and beside the racks there are respective spring cases 20, 50 each like the one first described and containing a similar drum and spring, as well as having the same tape 18 extended therefrom and connected centrally to the respective adjacent rack, so that on reciprocation of the rack in either direction 55 the tape is drawn outward against the tension of the spring, thus tending to draw the rack back to initial position whenever freed. The tension and strength of the springs is definitely proportioned to the mass of the weights, and the latter are intended to function by gravity and by centrifugal force developed by gyratory or turning movements of the plane in its flight.

While weights have been shown, other well known means for such purposes may be employed as found desirable whether operating by gravity or air current pressure, and the intermediate connections may be varied as found desirable.

The spring 22 associated with the rack 46, 70 gear 47 and weight 52 is preferably constructed so that when the plane is transversely horizontal the weight will be returned from either extreme to normal initial or neutral position of the parts, and when the craft becomes inclined laterally 75

in either direction, the weight will overcome the spring proportionately to effect operation of the rudder. The resistance of the spring should become progressively greater as the rack is moved, so that the spring will be capable of raising the weight from either extreme when the plane is in normal flight, and the control wheel is free.

In the use of the construction described, with the plane in normal flight, the pilot in order to make a normal quick turn grasps the wheel with one or both hands firmly so as to encompass both rim sections in the grasp of the hand, and turns the two sections as a unit in the proper direction—clockwise for a right hand turn with the structure illustrated. This turns the vertical rudder to move the tail to port, and operates the aileron to depress the starboard wing, causing a proper bank. When the proper degree of bank is attained the pilot opens his fingers sufficiently to release the lower rim section but still holding the one 41, and by the action of the automatic return spring devices acting on the rack 48 as well as air pressure on the aileron, the latter is returned to normal position and the ship then continues the turn without further increase of bank. At the same time the elevator is operated by depression of the heel of the pedal, to keep the head of the craft up, counter-acting tendency of the craft to nose downward when banked with the vertical rudder set as last indicated. When the turn has been nearly completed in this manner, the pilot again closes his fingers on the lower rim section and reverses the movement of the complete wheel comprising both rims—counter clock-wise, to come out of the right hand turn, and through an arc equal to that through which the wheel was moved to begin the turn. The determination of this is purely automatic and requires no judgment, for the hands having been retained in position on the upper rim, it is only necessary to return them to the normal position which they had at the beginning of the turn. This moves the vertical rudder back to normal so as to straighten the course of the ship, and at the same time operates the ailerons to trim the ship abeam. The pilot also at the same time releases the pedal to permit the horizontal rudder to return to normal, or he presses the toe of the pedal to effect such return positively. For a more gradual turn, after the ship has become banked by the operation of both rims as described, for beginning the turn, they are both released, permitting both the vertical rudder and the ailerons to assume normal position and then the elevator slightly raised by depression of the heel of the pedal. When such a turn is completed the rim 34 alone is then operated to level the ship abeam, and the elevator returned to normal flight position, and as soon as the ship is trimmed abeam, the wheel is released completely, freeing the rim 34 and allowing the return of the aileron to normal position as indicated. At any time during the turn, release of the wheel completely will cause the ship to automatically straighten its course and level off by action of the weights and springs, as indicated. In case of inadvertent excessive banking during a turn and beginning of a slip, or in case the ship goes out of trim abeam during normal flight, by release of the wheel either as to the lower section only or as to the complete wheel, and release of the pedal, the springs and weights will stop further digression from normal flight, and the weights will exert corrective ac-

tion to trim the ship and level off, as indicated in Figure 6. In this action the gear and weight 29—30 of the elevator control coact with the gears 47 and 49 of the rudder and aileron control and their respective weights, as will be understood. Thus, as indicated in Figure 6, in case of a slip to starboard, gear 49 and weight 51 will operate to lower the port wing, which will tend to stop the slip, and at the same time the gear 47 and weight 52 will operate the rudder to head the ship to starboard, further overcoming the slip. This will result in putting the ship slightly down by the head, and then the gear 29 and weight 30 coact through the elevator to bring the ship to a level course, as before described.

In case of a skid (see Fig. 8), and the aileron control is in neutral position, the centrifugal force developed in the weights acting from the axis of the turn to which the skid is due, will cause the weight 51 to swing toward the outer side of the ship, and result in operation of the aileron to properly bank the ship, the action being similar to that illustrated in Figure 6 as to the aileron; but the rudder would ordinarily be held manually in an opposite position.

For a turn such as the Immelman turn this control is especially useful, although the principal benefits of the invention are in facilitating ordinary simple maneuvers with a plane. For the Immelman turn, the wheel is grasped with both hands holding both sections firmly, and given a swift turn in the desired direction until the aileron at one side is lifted to right angles to the wing, whereby its acts as a brake on that one side, the rudder coacting therewith and a quick turn being effected while the plane continues on the same plane as before beginning of the turn. The further maneuvers of the plane will be understood by those versed in military aviation.

It will be noted that each section of the split wheel has a single radial bar as before described, and for maneuvers where individual operation of the two sections in opposite directions is required, the pilot may grasp the bars of respective sections in either hand and operate the sections independently. The bar 40 of the outer or upper section preferably extends transversely of the ship while the parts are in initial or neutral position, and the bar 36 of the inner or lower section preferably extends fore-and-aft at the same time.

For the Immelman barrel turn the pedal is operated to invert the ship with the elevator, and the bar 36 grasped and operated to right the ship with the aileron.

For recovery from spins and for other uses the two wheel sections may be independently operated by grasping the bars 36 and 40 as required.

It is important to note that by the construction presented in case of mistake by the pilot such as operation of either the aileron alone or the rudder alone the control devices automatically will cause proper guidance of the craft in a safe manner. Thus, if the aileron alone is operated, the transverse inclination of the plane thereby produced will cause the operation of the weight 52 and gear 47 to turn the rudder so as to head the plane in the direction of the low side of the craft. At the same time, the weight 30 will function to level the ship on the course to which it is turned. On the other hand, should the rudder alone be operated, centrifugal force

will act through the weight 51 to depress the wing at the inner side of the turn.

The terms of the claims relating to the transverse weight controls are intended to include various devices operative when a plane becomes transversely inclined, whether they respond to gravity, or unbalanced air pressures or currents.

The connections to the ailerons, rudder and elevator from the control devices, such as pedal, hand wheels and the weight devices may be of various kinds now familiar as found suitable and advantageous.

I claim:—

- 15 1. A steering wheel for air craft comprising inner and outer concentric revolvably mounted shafts, a rim for the wheel split in two parts divided to form two annular grip members in close relation adapted to be grasped together within one hand for the purposes described, a transverse cross bar fixed on one shaft and secured at its ends to one rim section, and a cross bar fixed on the other shaft at right angles to the first named bar normally and secured at its ends to the other rim section.
- 25 2. A control means of the character described, comprising a steering post, respective concentric shafts therein independently revolvble on their common axis, a vertical rudder operatively connected with the outer shaft, ailerons operatively connected with the inner shaft, a split wheel divided substantially in its major plane, to form complementary completely annular rim portions shaped, proportioned and adapted to be both enclosed in the grasp of the hand, the inner rim portion being connected to said outer shaft for operation of ailerons, the outer rim portion being connected to the inner shaft for operation of the vertical rudder, a fixed anchorage, and separate yielding means connected between the an-

chorage and the shafts respectively normally and inherently operative to move the shafts and rim portions from operated positions in either direction to a predetermined normal position of fixed location, for the purposes described.

3. A steering control wheel for airplanes comprising concentric independently revolvably mounted separate shafts, airplane controls connected respectively to the shafts, respective annular concentric rim members fixed on the shafts, said rim members being of identical radius from the axis of the shafts, and being spaced in juxtaposition with an exceedingly small space therebetween, the two rim members having such measurement in cross section and 15 opposite outer faces that taken together correspond to the normal cross section of a single steering rim, whereby both rim members may be grasped within a single hand for normal rotation customary with a single one-piece rim. 20

4. The structure of claim 3 in which the two rim members have opposed faces adapted to be pressed into coengagement to frictionally oppose relative movement of the two when pressed together, the mounting of the two rim members including resilient support means yieldable to the grip of a pilot, but rigid tangentially, whereby the two rim members may be pressed into frictional coengagement by the grip of the hand for the purposes described. 25

5. The structure of claim 3 in which the rim members are respectively shaped peculiarly whereby to permit holding or release of the lower rim member at will by opening or closing the digits of the hand, and whereby the upper 35 rim member is differently formed, whereby it may be held while the digits are extended. 30

WALLACE O. JAMES.
